UNITED STATES PATENT OFFICE.

LLOYD P. WALKER, OF BELMONT, MASSACHUSETTS.

CRUSHING MACHINE.

Application filed July 23, 1927. Serial No. 207,987.

This invention relates to a crushing machine.

The object of the invention is to provide a novel and superior construction of crushing machine of the type in which the movable crushing member is suspended at one of its ends, and which may be operated more efficiently than other crushing machines of this type of which I am aware.

10 A further and more specific object of the invention is to provide a novel and improved gyratory crusher of the type having the crushing head suspended and in which the gyratory crushing motion is imparted to the suspended head in a novel and superior manner.

With these objects in view and such others as may hereinafter appear, the invention consists in the crushing machine and in the 20 structures, arrangements and combinations of parts hereinafter described and particularly defined in the claims at the end of this specification.

In the drawing, Figure 1 is a vertical sectional view of a gyratory crushing machine embodying the features of the present invention; Fig. 2 is a horizontal section on the line 2—2 of Fig. 1; and Fig. 3 is a vertical sectional detail taken on the line 3—3 of Fig. 2.

30 Referring to the drawing, the present improved crushing machine comprises in general a pair of cooperating crushing members, one of which is suspended to be capable of a gyratory motion about its point of suspension, and provision is made for imparting such gyratory motion to the suspended crushing member in a manner such as to enable the crushing machine to be operated at relatively high crushing speed as compared with any of 40 the standard crushing machines now upon the market. In the preferred embodiment of the invention the gyratory crushing motion is imparted to the suspended crushing member by a plurality of eccentric driving members 45 connected to said member, the number and size of said eccentric driving members being correlated to maintain a total bearing area sufficient to sustain the maximum crushing load and at the same time to enable the crushing machine to be operated at a relatively high crushing speed as compared with standard machines now upon the market.

In the illustrated crushing machine, 10 represents a hopper formed at the upper end of a frame 12 and through which the material to be crushed is introduced into the crushing

machine. The frame 12 operatively supports a stationary crushing member 13 with which a tapered gyratory crushing member 14 is arranged to cooperate to perform the crushing 60 operation.

Provision is made for suspending the crushing member 14 at its upper end and for this purpose the crushing member 14 is mounted upon a shaft 15 having a reduced 65 portion 16 extended through an enlarged hole 18 in a cap member 20 formed in arms 22 extended inwardly from opposite sides of the hopper 10. The upper end of the reduced portion 18 of the shaft is threaded and is 70 provided with a nut 24 which rests upon a collar 26 whose lower end is rounded and arranged to have a bearing in a rounded portion of the cap 20, to permit the shaft 15 and the crushing member 14 carried thereby to 75 gyrate about the bearing between the collar 26 and the cap as will be evident from an inspection of Fig. 1.

The lower portion of the shaft 15 is extended into a block 30 located within a hub 32 supported upon arms 34 extended inwardly from the frame 12 at near the lower portion thereof. A universal member 38 is provided between the end of the shaft 15 and the walls of the opening in the block 30 to permit universal movement between the shaft and the block. The block 30 is provided with a plurality of eccentric driving members 40 herein shown as comprising sleeves mounted upon shafts 42 secured in the upper and lower 90 plates 43, 44 of the hub 32, and the eccentric sleeves 40 have bearings within the block 30 and are preferably arranged symmetrically about the axis of the crusher. Each eccentric sleeve is provided upon its lower end with 95 a pinion 48 and all of the pinions 48 are arranged to mesh with a central driving gear 49 formed on the upper end of a shaft 50, and which gear 49 is arranged to be rotated from a suitable source of power through the driving 100 pulley 52, shaft 53, and cooperating bevel gears 54, 55. The shaft 53 is shown as having bearings 56 in the frame 12 of the crusher and an outer bearing 57.

In the operation of the machine the block 105 30 is reciprocated laterally within the hub 32 by the eccentric sleeves 40 and imparts through the universal 38 an eccentric motion to the lower end of the shaft 15, and consequently in this manner the crushing member 14 is caused to gyrate and to cooperate 110 with the stationary crushing member 13 to

perform the crushing operation. In the illustrated machine the crushing material is discharged through an annular opening 60 and falls down the chute 62 to be discharged.

5 In order that the present machine may be operated with maximum efficiency, the number and size of the eccentric driving members are correlated to materially diminish the size of the individual eccentric driving members 10 and to compensate for the diminished size thereof by an increased number thereof. By the provision of a sufficient number of eccentrics it is possible to maintain the total bearing area between the eccentrics and the 15 crushing member sufficient to carry the crushing load with safety and at the same time the increased number of eccentrics enables their individual size to be cut down as compared with standard crushing machines so as to enable the crushing speed of the machine to be 20 materially increased over the permissible speed of standard crushing machines. In this manner it is possible to operate the crushing machine at speeds which will produce a capacity 25 substantially double that of a corresponding size of standard crushing machine, or on the other hand it is possible to obtain the same capacity as any of the standard crushing machines with a crushing machine of materially 30 less size.

While in the illustrated machine eccentric sleeves have been shown as the preferred form of eccentric driving member for the particular type of crushing machine shown, it is to be understood that other forms of eccentric driving members may be used if found advantageous, such for example as eccentric shafts.

40 While in the drawing I have illustrated a crushing machine embodying the present invention in which the movable crushing head is suspended from the top, it will be understood that as used throughout this specification and in the claims the word "suspended" 45 is intended to define any construction in which the crushing head is supported at one end.

While the preferred embodiment of the invention has been illustrated and described, 50 it will be understood that the invention may be embodied in other forms within the scope of the following claims.

Having thus described the invention, what is claimed is:—

55 1. A crushing machine having, in combination, a pair of cooperating crushing members, means for suspending one of the crushing members to permit it to gyrate, and means for imparting a gyratory motion to the suspended crushing member to perform the crushing operation, including a plurality of eccentric driving members operatively connected with said suspended crushing member and driving means for said eccentric driving members.

60 65 2. A crushing machine having, in com-

bination, a pair of cooperating crushing members, means for suspending one of the crushing members to permit it to gyrate, and means for imparting a gyratory motion to the suspended crushing member to perform the 70 crushing operation, including a movable member connected to said gyratory crushing member, and a plurality of eccentric driving members having bearings in said movable member and driving means for said eccentric 75 driving members.

3. A crushing machine having, in combination, a pair of cooperating crushing members, means for suspending one of the crushing members to permit it to gyrate, and means 80 for imparting a gyratory motion to the suspended crushing member to perform the crushing operation, including a movable member, a plurality of eccentric driving members having bearings in said movable member 85 and driving means for said eccentric driving members, and a universal connection between said movable member and the gyratory crushing member.

4. A crushing machine having, in combination, a pair of cooperating crushing members one of which is provided with a shaft extending beyond the opposite ends of the crushing member, means cooperating with one end portion of the shaft for suspending the crushing member to permit it to gyrate, and means for imparting a gyratory motion to the suspended crushing member, including a movable member provided with an opening into which the second end of said shaft is extended, a plurality of eccentric driving members having bearings in said movable member, and driving means for said eccentric driving members.

5. A crushing machine having, in combination, a hollow frame, a hollow stationary crushing member supported thereby, a conical crushing head suspended from the frame and positioned within said stationary crushing member, and means for imparting a gyratory motion to said suspended crushing member including a plurality of eccentric driving members, driving means for said eccentric driving members, and connections between the eccentric driving members and suspended 100 crushing member.

6. A crushing machine having, in combination, a pair of cooperating crushing members, means for suspending one of the crushing members to permit it to gyrate, and means for imparting a gyratory motion to the suspended crushing member to perform the crushing operation, including a plurality of eccentric driving members the number and size of which are correlated to permit the crushing machine to be operated at relatively high crushing speed as compared with standard crushing machines, and driving means for said eccentric driving members.

7. A crushing machine having, in combina-

tion, a pair of cooperating crushing members, means for suspending one of the crushing members to permit it to gyrate, and means for imparting a gyratory motion to the suspended crushing member to perform the crushing operation, including a movable member, a plurality of eccentric driving members having bearings therein, driving means for said eccentric driving members, a universal con-

nection between said movable member and 10 the suspended crushing member, gearing for driving the eccentric driving members in unison, and a housing enclosing the movable member and said gearing.

In testimony whereof I have signed my 15 name to this specification.

LLOYD P. WALKER.
